Mr. Hallick & Hallick

Atty,

UNITED STATES PATENT OFFICE.

WILLIAM S. ROBERTS, OF BRADFORD, PENNSYLVANIA.

SUCKER-ROD WRENCH AND ELEVATOR.

SPECIFICATION forming part of Letters Patent No. 246,342, dated August 30, 1881.

Application filed June 14, 1881. (No model.)

To all whom it may concern:

Be it known that I, WILLIAM S. ROBERTS, of Bradford, McKean county, Pennsylvania, have invented new and useful Improvements 5 in Sucker-Rod Wrenches and Elevators; and I do hereby declare that the following is a full, clear, and exact description thereof, reference being had to the accompanying drawings and the letters or figures of reference marked there-
10 on.

My invention relates to devices for handling oil-well sucker-rods when putting them in or removing them from the well, which devices are known as "sucker-rod wrenches and ele-
15 vators."

The tool consists of a wrench-head with trun-
20 nions or pintles on two of its sides, opposite
each other, the line of which is transverse
the wrench opening or slot, to which pintles
is pivoted a forked handle, having at its ex-
tremity a swivel. When the forked handle lies
25 horizontal with the wrench-head it can serve
as the handle or lever of the wrench, and when
turned in a vertical position it can serve as a
bail by which to lift the sucker-rod.

My invention consists in providing upon the
wrench-head a latch which, when the handle
is used as a bail, will sufficiently close the slot
30 to prevent the rod slipping out, and which,
when the device is used as a wrench, will fall
back and leave free access for the shank of the
sucker-rod in the slot of the wrench-head.

My device is shown in the accompanying
drawings, as follows: Figure 1 shows the de-
35 vice in position to be used as a wrench. Fig.
2 shows it in position to be used to draw up
the sucker-rods or lower them. Fig. 3 shows
an analogous construction.

The letters of reference indicate parts, as
40 follows:

A is the handle; B, the wrench-head; B',
the opening or slot in the wrench-head; b, the
latch; a, the eccentric or cam on the handle
for moving the latch; S, the spring which keeps
45 the latch back when not pushed forward by
the cam.

It is not new to provide means upon such a
device as is here under consideration for hold-
ing the sucker rod in place when the device is
used as an elevator. This has been done by 50
placing a finger on the handle A, which, when
the handle is in a vertical position, will lie in
front of the sucker-rod and prevent it slipping
out of the slot B'. This finger is liable to break
off in usage. 55

My invention consists in providing a latch
upon the head B which will be thrown out into
the opening B' and prevent the rod slipping
out when the handle is in a vertical position.
In Figs. 1 and 2 this latch is shown as a flat 60
pivoted tongue lying in a recess, and project-
ing to one side far enough to be acted upon by
the cam a on the handle when it is turned up.

The operation of this device is fully shown
in Figs. 1 and 2. The spring S may be used 65
or not, as desired. In the construction shown
in Fig. 3 the latch consists of a spring-bolt, b',
which is operated upon by a cam, a'. I con-
sider these two forms as entirely analogous.
Other analogous forms might be shown—such 70
as a plate pivoted on the face of the head B, for
instance; but I believe I have shown enough
to fully illustrate my invention.

What I claim as new is—

1. The combination, within a sucker-rod 75
wrench and elevator, of a latch upon the wrench-
head, which is operated to form an obstruction
in the opening B' when the handle A is turned
up, substantially as and for the purposes set
forth. 80

2. In a sucker-rod wrench and elevator, the
combination of the handle A, wrench-head B,
latch b, and cam a, substantially as set forth.

In testimony that I claim the foregoing I have
hereunto set my hand this 20th day of May, 85
1881.

W. S. ROBERTS.
